(57) CLAIM

The ornamental design for a display screen or portion thereof with animated icon, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is the first image in a sequence for a display screen or portion thereof with animated icon showing my new design; FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof; and,

FIG. 10 is the tenth image thereof.

The broken-line outline of a circle shown with a short-and-long dash pattern in FIGS. 1-10 illustrates the bounds of the icon and forms no part of the claimed design.

The inventor contemplates that other embodiments of their design may include any part, portion, element or combination of elements of the claimed design.
